DAYTON ULREY AND DANIEL I. MAYNE, OF WILKINSBURG, PENNSYLVANIA, AS-
SIGNORS TO WESTINGHOUSE ELECTRIC AND MANUFACTURING COMPANY, A COR-
PORATION OF PENNSYLVANIA.

AUTOMATIC ELECTRIC FLASHER.

Application filed June 28, 1923. Serial No. 648,245.

Our invention relates to circuit interrupters and more particularly to the type known as flashers.

An object of our invention is to provide a fluid-containing flasher with means for eliminating breakage incident to the transportation thereof.

Another object of our invention is to provide a flasher of the type containing a fluid and a float having means for preventing the float from destroying the container during transportation.

Another object of our invention is to provide a flasher of the fluid type having a time interval between the interrupting and the closing of an electrical circuit.

It is also an object of our invention to provide a flasher with means for utilizing the surface tension of the contained liquid for securing a time interval between the closing and the interrupting of the electrical circuit.

In practicing our invention, a receptacle, which is usually of sealed glass, is provided with an electrical conducting fluid and a floating member whose position is normally controlled by a solenoid, which is so arranged that it raises and lowers the floating member, thereby controlling the level of the liquid in the receptacle in such manner that the fluid interrupts and closes an electrical circuit. To prevent the float from destroying the container during shipment, we have found it advisable to interpose cushioning means between the ends of the floating member and the walls of the receptacle. We have also found that a relatively long, shallow chamber, in which the electrical contact is made or interrupted, is advantageous for producing a desired time interval in the operation of the flasher.

Our invention is an improvement over the structure shown and described in the application of Dayton Ulrey, Serial No. 622,878, filed Mar. 5, 1923, (Case No. 10096), and assigned to the Westinghouse Electric & Manufacturing Company.

In the accompanying drawings:

Fig. 1 is a sectional view of a flasher together with the associated electrical circuits embodying our invention.

Fig. 2 is a similar view of another form of flasher.

Fig. 3 is a detail view showing the posi-

tion assumed by the fluid while the electrical circuit is interrupted.

In the several figures of the drawing, similar reference numerals indicate like parts.

In the preferred form of our invention, a flasher 1, having a receptacle or container 2, which may be in the form of a sealed glass tube, is adapted for intermittently connecting a supply circuit 3 to a circuit 4, such as a street lighting circuit containing a plurality of lamps 5 which may be arranged either in series or parallel connection. A solenoid 6 surrounds the receptacle 2 and is connected to the circuit 3 in such manner that its circuit is interrupted simultaneously with the circuit 4. A variable resistor 7 may be placed in circuit with the solenoid 6 for a purpose to be hereinafter discussed.

The container 2 comprises an elongated section 11 containing a conducting liquid 12, such as mercury and an extension 13 having a restricted passage 14, which terminates in an enlarged inverted U-shape chamber 15. Electrical contact members 16 and 17 are inserted through the wall of the chamber 15 and make contact with the liquid 12. The central portion 18 of the chamber 15 has a relatively long, flat surface for a purpose to be hereinafter discussed. The contact members 16 and 17 are placed on opposite sides of the portion 18.

A member 19 of magnetizable material is in the elongated section 11 and is adapted to float on the fluid 12. Cushioning means in the form of spiral springs 21 are provided on the opposite ends of the float member 19 in such manner that they serve as buffers between the ends thereof and the end walls of the elongated section 11.

In the operation of our improved flasher, current traverses the solenoid 6 attracting the float 19 in a manner to cause it to change its position relative to the fluid 12. This attraction may either lift the float from the fluid 12 or depress it further therein.

In the form of our invention shown in Fig. 1, the solenoid is adapted to lift the float 19. As the float 19 is drawn upwardly, the fluid from the chamber 15 tends to traverse the restricted passage 14 until the electrical circuit between the contacts 16 and 17 is interrupted across the surface 18.

So soon as the electrical connection is interrupted the solenoid 6 and the lamps 5 are

de-energized. The de-energization of sole-
noid 6 allows the float 19 to fall back into
the liquid 12 with the result that a movement
of the fluid 12 from the section 11 to the
chamber 15 takes place through the passage
14. When a sufficient amount of fluid has
returned to the chamber 15, electrical connec-
tion is again made across at the surface 18
and the solenoid 6 and lamps 5 are again
10 energized.

In order that there be a sufficient time lag
between the closing and interrupting of the
electrical circuit, a variable resistor 20 may
15 be interposed in circuit with the coil 6 there-
by controlling the current strength and there-
fore the ampere-turns effective upon the float
19. By regulating the cross-sectional area
of the passage 14, the rate of movement of
the fluid between the chamber 15 and the
20 section 11 may also be regulated.

We have also found, that by making the
surface 18 long and broad it is possible to
employ the surface tension of the liquid it-
self for producing a time lag. We have ob-
25 served that the particles of the fluid 12 tend
to cohere rather than move along the surface
18. Stated in other words, as shown in Fig.
3, the fluid tends to pile up rather than
spread in a thin sheet over the surface 18.
30 By proper design of the surface 18, the sur-
face tension or cohesion of the fluid may be
utilized to give a further time lag in the
opening and closing of the circuit between
the contacts 16 and 17.

35 We have found that frequent breakage of
receptacle 2 during transportation has been
produced by impact of the float on the walls
of the receptacle when no cushioning means
is provided. In order to avoid this loss, we
40 have provided resilient means, such as
springs 21, attached at the ends of the float
member. Longitudinal movement of the
floating member is accordingly cushioned
when the float comes in contact with the ends
45 of the section 11. Relatively no lateral
movement of the float 19 is experienced in
the section 11 by reason of the small clear-
ance between the inner surface thereof and
the outer surface of the float member 19.

50 In the form of our invention shown in
Fig. 2, we have provided a longitudinal sup-
port member 22 which extends lengthwise of
the section 11. The float member 19 is
provided with a longitudinally extending
55 opening 23 through which the rod 22 ex-
tends with a loose fit. Resilient means, such
as springs 24, are loosely mounted on the rod
22 adjacent to the ends of the floating mem-
ber 19 to cushion longitudinal movements of
60 the float member in the same manner as do

the springs 21, Fig. 1. One of the contact
members 16 and 17, shown in Fig. 1, may
be eliminated by attaching a conductor at
one end of the rod 22. In all other structural
features and operation the two flashers are 65
identical.

It will thus be seen that we have provided
a new and improved flasher in which means
are provided for producing a time lag be-
tween the interrupting and closing of an 70
electrical circuit, by making use of the sur-
face tension or cohesion of a conducting
fluid. We have also provided new and im-
proved cushioning means for protecting the
75 flasher from destruction during the trans-
portation thereof.

Our invention is not limited to the specific
structure illustrated, as it may be variously
modified without departing from the spirit
and scope of the invention, as set forth in the 80
appended claims.

We claim as our invention:

1. In a switch structure, a vessel, a con-
ducting fluid in said vessel, means for caus-
ing said fluid to interrupt and close an elec-
trical circuit by changing the level thereof,
and means for causing a time lag in the 85
movement of said fluid comprising means for
utilizing the surface tension of said fluid
and means for controlling the delivery of 90
fluid to the last said means.

2. In a switch structure, a receptacle, a
conducting fluid in said receptacle, means for
causing said fluid to interrupt and to close an
electrical circuit by changing the level there-
of, and means whereby the surface tension 95
of said fluid is employed for causing a time
lag in the movement of said fluid comprising
a chamber having a relatively long flat
surface over which the fluid moves in clos-
ing the circuit and means for controlling the 100
delivery of fluid to the said chamber.

3. In a switch structure, a receptacle, a
conducting fluid in said receptacle, means for
causing said fluid to interrupt and close an 105
electrical circuit by changing the level there-
of, and means whereby the surface tension
of said fluid is employed for effecting a
time lag in the movement of said fluid com-
prising an extension to said receptacle hav- 110
ing a restricted passage terminating in a
relatively long and shallow chamber having
a substantially flat surface over which the
fluid moves in closing the circuit.

In testimony whereof, we have hereunto 115
subscribed our names this 20th day of June,
1923.

DAYTON ULREY.
DANIEL I. MAYNE.
